UNITED STATES PATENT OFFICE

159,905

CHILD'S COSTUMER

Irmi Ann Gross, New York, N. Y.

Application July 19, 1949, Serial No. 3,993

Term of patent 7 years

(Cl. D33—8)

To all whom it may concern:

Be it known that I, Irmi Ann Gross, a citizen of the United States of America, residing in New York city, county of New York, and State of New York, have invented a new, original, and ornamental Design for a Child's Costumer, of which the following is a specification, reference being had to the accompanying drawing, forming part thereof, wherein,

I claim:

The ornamental design for a child's costumer, substantially as shown.

IRMI ANN GROSS.
